Des. 191,766
Patented Nov. 14, 1961

191,766

COMBINED STEAM AND SPRAY IRON

Andrew S. Knapp, St. Louis, Mo., assignor to Knapp-
Monarch Company, St. Louis, Mo., a corporation of
Delaware

Filed June 13, 1960, Ser. No. 60,934

Term of patent 14 years

(Cl. D49—6)

Fig. 1

Fig. 2

FIGURE 1 is a perspective view of a combined steam and spray iron, showing my new design;
FIGURE 2 is side elevational view thereof;
FIGURE 3 is a top plan view thereof;
FIGURE 4 is a front elevational view thereof; and
FIGURE 5 is a rear elevational view thereof.

I claim:

The ornamental design for a combined steam and spray iron, substantially as shown.
